UNITED STATES PATENT OFFICE.

CECIL M. SYKES, OF MILFORD, CONNECTICUT, ASSIGNOR TO THE HAYES MESEROLE MFG. CO., OF MILFORD, CONNECTICUT, A CORPORATION.

PENCIL SHARPENER.

Application filed June 8, 1926. Serial No. 114,381.

This invention relates to improvement in pencil sharpeners and particularly to pencil sharpeners comprising a conical pencil-tip-receiving recess formed with a slot in which 5 a blade is mounted, and especially to pencil sharpeners of this type in which the cutter is mounted in a sheet-metal casing, and is an improvement on the construction shown and described in United States Patent No. 1,543-, 10 226, granted June 23, 1925. The object of this invention is to so construct the housing that the cutter will be firmly mounted therein to resist the pressure of the pencil when forced into the cutter, and the invention consists in the construction as hereinafter 15 described and particularly recited in the claims.

In the accompanying drawings:

Fig. 1 is a side view of a pencil sharpener 20 constructed in accordance with my invention;

Fig. 2 is a front view of the same;

Fig. 3 is a vertical sectional view of the same;

Fig. 4 is a transverse sectional view of the same; and

Fig. 5 is a front view of the housing with the cutter-frame removed.

In carrying out my invention, I employ a 30 cutter 10 of substantially usual form with a tapered recess 11 for the reception of the end of a pencil to be sharpened. This cutter is formed with a longitudinal slot 12 and attached to the cutter by a screw 13 is a 35 blade 14, the edge of which extends into the chamber 11. The inner end of the cutter is formed with a tubular bearing 15 and the outer end with a stud 16. The bearing 15 and stud 16 are mounted in opposite ends 40 17 and 18 of a frame, which is struck up from sheet-metal, with side-walls 19 and 20, the bottom 21, side-walls 19 and 20 and end-piece 17 being preferably formed from a single piece of metal, the end 18 being separately formed and connected to the frame 45 by side-lugs 22 and bottom-lugs 23 forming an integral structure, and the frame forming a receptacle to catch shavings.

The housing for the cutter, like the housing 50 of the patent above referred to, is formed from a strip of sheet-metal bent into U-shape, with the edges 24 turned outward to form flanges by which the housing may be secured to a support. Extending transversely across

the housing is a floor 25 forming a chamber 55 for the reception of the cutting mechanism, the floor being formed at the center with a downwardly-extending U-shaped extension 26 for the purpose as will hereinafter appear, and at its forward edge with upwardly-extending lips 27.

Secured to the outer end of the stud 16 is a crank-handle 28.

Instead of entering the cutter from the front of the housing, as in the patent above 65 referred to, it is entered from the rear, the depression 26 in the bottom forming a clearance for the handle 28, and the lips 27 forming stops to prevent the further forward movement of the cutter.

The device is used in the usual way by inserting the end of a pencil into the chamber 11 and holding it while the crank is turned and the cutter revolved, but in this construction, the pressure of the pencil into the 70 cutter tends to force the cutter forward against the lips 27, which form stops to prevent further forward movement, so that it is impossible to force the cutter out of the housing during the sharpening operation.

I thus provide without increased cost of manufacture, a pencil sharpener in which the cutter is firmly mounted in the housing.

I claim:

1. A pencil sharpener, comprising a cutter, a frame in which the cutter is mounted, said cutter provided with a crank-handle, and a housing formed with a transverse floor, the central portion of the floor outwardly bowed and the forward edge of the floor 85 formed with lips against which the cutter-frame bears.

2. A pencil sharpener, comprising a cutter-frame, a cutter mounted in the ends of the said frame and provided with a crank-handle, a housing formed from a strip of sheet-metal bent into U-shape and provided with a transverse floor upon which the cutter-frame rests, said floor formed with a centrally-arranged U-shaped bend and at its 90 rear edge with upwardly-extending lips forming stops for the cutter-frame, whereby the cutter-frame is entered from the forward end, the central depression in the floor providing clearance space for the said handle.

In testimony whereof, I have signed this specification.

CECIL M. SYKES.
